UNITED STATES PATENT OFFICE.

ARDO HERING, OF NEW YORK, N. Y.

DESIGN FOR A HOLDER FOR BOTTLES, GLASSES, AND SIMILAR ARTICLES.

No. 38,243.

Specification for Design.

Patented Sept. 18, 1906.

Application filed June 7, 1906. Serial No. 320,681. Term of patent 14 years.

To all whom it may concern:

Be it known that I, ARDO HERING, a citizen of the United States, residing at New York, in the county and State of New York, have invented a new, original, and ornamental Design for Holders for Bottles, Glasses, and Similar Articles, of which the following is a specification, reference being had to the accompanying drawing, forming part thereof.

The figure is a perspective of a holder, showing my new design.

I claim—

The ornamental design for holder for bottles, glasses and similar articles, as shown.

ARDÖ HERING.
